UNITED STATES PATENT OFFICE.

WILLIAM L. HOOVER AND JOHN NEWCOMB, OF INDIANAPOLIS, INDIANA.

FANNING-MACHINE.

SPECIFICATION forming part of Letters Patent No. 278,795, dated June 5, 1883.

Application filed August 14, 1882. (No model.)

To all whom it may concern:

Be it known that we, WILLIAM L. HOOVER and JOHN NEWCOMB, both of the city of Indianapolis, and State of Indiana, have invented 5 a new and useful Fanning-Machine, of which the following is a specification.

Our invention relates to a method of providing a rocking-chair with a fan, so constructed that the fan shall revolve with a reciprocal motion corresponding with the backward and forward movements made in rocking. The fan is useful on a hot day and when the flies are thick.

The accompanying drawings illustrate the 15 manner and method of constructing the fan and making the connections with the rocking-chair.

Corresponding letters in the different figures denote corresponding parts.

20 Figure 1 is a perspective view of our invention.

A is a rocking-chair.

C is a cross-piece, which goes under the rockers, and is fastened by the set-screw H. F is 25 a cord, which runs from the said piece under said rockers to the spool E. The cord passes two or three times around the spool to the spiral spring G, and the other end of said spiral is attached to a cord, which in its turn is at-

30 tached to the upright D. Thus the cord F runs from the place of its fastening, at the ends of the piece C, around and over the spool E to the fastening below in the upright D. If a person takes a seat in the chair A, it is plain 35 that rocking back and forth will, by means of the cord on the spool E, cause the fan I to revolve with a reciprocal motion correspond-

ing to the motion of the person rocking. The strain upon the spring G causes the chair to 40 recover its position, and the fan moves in correspondence therewith, having the said reciprocal motion.

Fig. 2 is a section of the upright D, showing more in detail the cord F and its manner of passing around the spool E. It also shows the 45 details of the construction of said spool E and its insertion into the main part of the axle M, into which the fan I, as shown in Fig. 1, is also inserted.

Fig. 3 is a view in detail of the manner in 50 which the attachment is made of the cross-piece C to the rockers. B is the angular piece by means of which the cross-piece C is fastened to the under part of rockers P. K is a slot in said piece C, through which the angular iron 55 B is caused to slide in order that rockers of different widths apart may be used. L is a box, in which the spool E runs. The wings of the fan I are four in number.

An important feature is the elastic section 60 G in the cord F. By means of this we obtain one motion of the fan. The reaction of the spring G draws the fan backward, completing its reciprocal motion.

It is obvious that this invention may be applied in a variety of methods. For instance, 65 a rocking-chair may be made with a pedestal, so as to dispense with the platform.

The fan may be applied to a cradle as well as to a rocking-chair.

70

We claim as our invention—

In a fanning device, the upright piece D, provided with the spring G, having the cord F attached thereto, said cord being passed around the spool E, and the other end of said 75 cord being attached to rockers, substantially as described and shown, and for the purpose set forth.
